CIRCUIT INTERRUPTER

John K. Hodnette, Sharon, Pa., assignor to Westinghouse Electric & Manufacturing Company, East Pittsburgh, Pa., a corporation of Pennsylvania

Application October 30, 1941; Serial No. 417,150

42 Claims. (Cl. 200—116)

This invention relates to electric circuit interrupters generally, and more specifically to circuit breakers especially of the automatic reclosing type.

At the present time, it is common practice to protect individual distribution transformers and branch feeder circuits with a fuse having a metallic link which melts on overcurrents to interrupt the circuit. Most fuses are open to the atmosphere and consequently may give faulty operation due to oxidation and deterioration of the link. The life of a fuse is limited to a few operations, and after blowing the fusible link must be manually replaced to restore service on the circuit protected. To overcome the last of these disadvantages, so-called "repeating" fuses have recently been used. These comprise a plurality of fuses with one normally in the circuit, and with automatic means for connecting another in the circuit when said one fuse blows. Although this type of fuse structure provides for better continuity of service, blown fuses must still be manually replaced, and they are also subject to the other disadvantages of fuses set forth above.

To overcome the above-mentioned disadvantages of fuses, it has been proposed to provide an automatic reclosing oil circuit breaker as a protective device to replace fuse structures. Such circuit breakers must be made small in size so as to be suitable for pole mounting, they should be completely self-contained, and should operate to lock the breaker contacts open after a predetermined number of reclosures, and reset to their original position following any number of reclosures less than said predetermined number. Thus far, the art has failed to develop a fully satisfactory circuit breaker of this type which satisfies all of the foregoing requirements relative to size and operating characteristics.

Accordingly, one object of this invention is to provide a novel small automatic reclosing circuit breaker of the type described.

Another object of this invention is to provide a novel circuit breaker operating mechanism which shall be effective to lock the breaker contacts in open circuit position only in response to a predetermined number of closely successive circuit interrupting operations.

Another object of this invention is to provide in a circuit breaker utilizing fluid pressure generated by the arc for opening the breaker contacts, a novel arc chamber construction especially adapted for the efficient interruption of arcs of both high and low current values.

Another object of this invention is to provide

in a circuit breaker of the type described, novel means for mechanically separating the breaker contacts at least enough to draw an arc in response to predetermined circuit conditions.

Another object of this invention is to provide a circuit breaker of the type described with electroresponsive means for both opening and closing the breaker contacts.

Still another object of this invention is to provide in a circuit breaker of the type utilizing fluid pressure generated by the arc to fully separate the breaker contacts, additional means responsive to persistent small current arcs for positively separating the breaker contacts.

These and other objects of this invention will become more apparent upon consideration of the following detailed description of preferred embodiments thereof taken in connection with the attached drawings, in which:

Fig. 1 is a longitudinal cross-section view of a circuit breaker constructed in accordance with one embodiment of the invention;

Fig. 2 is a central longitudinal cross-sectional view similar to Fig. 1, but taken at right angles to the section of Fig. 1;

Fig. 3 is an enlarged view of the operating mechanism shown in Fig. 1;

Fig. 4 is an enlarged view of the operating mechanism as shown in Fig. 2 of the drawings;

Fig. 5 is a view similar to Fig. 3, but showing the parts in a position wherein the circuit breaker contacts are open corresponding to an initial circuit interrupting operation;

Fig. 6 is a view similar to Fig. 5, but shows the parts in a position wherein the circuit breaker contacts are locked open;

Fig. 7 is a longitudinal cross-sectional view of a circuit breaker illustrating another embodiment of the invention;

Fig. 8 is a partial longitudinal cross-sectional view illustrating a modified form of contact operating mechanism;

Fig. 9 is a view similar to Fig. 8, but showing a still further modified form of contact operating mechanism;

Fig. 10 is a longitudinal cross-sectional view of another modified form of circuit breaker per se;

Fig. 11 is an elevational view partially in section of a still further modified form of circuit breaker operating mechanism; and

Fig. 12 is a partial longitudinal cross-sectional view of still another modified form of circuit breaker constructed in accordance with this invention.

55

In the drawings there is illustrated reclosing circuit breaker constructions wherein the contacts are first initially opened by mechanical means controlled by a current-responsive element, together with means for biasing the contacts closed following a circuit interrupting operation. There is also provided means responsive to a predetermined number of successive interrupting operations to lock the breaker contacts open, and in the event of the occurrence of successive interrupting operations less than said predetermined number, the lockout means is adapted to be reset so that the apparatus will be in condition to lock the contacts open in the event of the occurrence of said predetermined number of interrupting operations in the future. The breaker illustrated in the drawings also is especially constructed so that pressures developed by the arc formed when the contacts are initially separated aid to obtain further separation of the contacts irrespective of the current value of the arc.

Referring to the drawings, there is shown in Figs. 1 to 6 a circuit breaker which may be enclosed in an insulating casing 2 which may be of any desired insulating material, preferably porcelain or the like, and which has an open top and closed bottom, as viewed in Figs. 1 and 2. The closed bottom of casing 2 is provided with a substantially central aperture 4 for the reception of a terminal bolt 6 having an enlarged head 8 adapted to be positioned interiorly of casing 2, with packing material 10 interposed between the head of the bolt and casing wall to seal opening 4. Contact bolt 6 is secured in position by a nut 12, with a washer 13 interposed between the nut and casing 2, and a second nut 16 may be provided on bolt 6 for securing a conductor 14 thereto.

Casing 2 is preferably provided intermediate its ends with a smooth outer peripheral surface 18 for reception of a clamping strip or other securing means for supporting the interrupter on a cross-arm or other support. The upper end of casing 2 is provided with a supporting channel member 20 secured to the casing, for example, as by molten material poured in between the channel and casing and forming locking projections between integral ribs 22 on the outer surface of the casing. The support 20 is for the purpose of securing a casing cover in operative position with respect to the casing.

A cover assembly 26 is shown as mounted over the open top of the casing and includes a generally tubular casting 28 having a peripheral flange 30 adapted to be seated on the open end of the casing, and be secured to support 20 in any desired manner (not shown).

The particular insulating casing described above, together with the bottom contact assembly therefor, and support 20 for a casing cover are substantially like those disclosed and claimed in the copending applications of J. M. Wallace, Serial No. 345,051, filed July 12, 1940, and H. L. Rawlins, et al., Serial No. 346,300, filed July 19, 1940, now Patent No. 2,318,421 granted May 4, 1943, both assigned to the same assignee as this invention. Accordingly, for a more complete description of this structure, reference is hereby made to the above-identified copending applications.

The circuit breaker operating mechanism is supported from cover assembly 26 by an insulating supporting plate 32, which may be of any desired insulating material, such as fibre or the

like, and secured to cover casting 28, for example, as by bolts 34. A supporting column 38 for the interrupter chamber 42 and operating mechanism is preferably secured to the lower end of insulating supporting plate 32, for example, as by bolts 36, and the lower end of the supporting column is preferably fixed to, or may be integral with, a top cap 40 of the interrupter unit 42. The interrupter unit includes an insulating tube 44 which also may be made of any desired insulating material, preferably fibre or the like, and this tube is threaded at each end thereof for securement to top cap 40 and lower end cap 46. It will be noted that lower end cap 46 has a reduced outer end portion forming a shoulder 48 on which one end of a coil compression spring 50 is adapted to be seated, with the other end thereof bearing against the head 8 of contact bolt 6 to insure good electrical contact under pressure between end cap 46 and bolt 6. Coil spring 50 may be of any desired resilient conducting material, such, for example, as a copper alloy. Lower end cap 46 is provided with a threaded aperture substantially centrally thereof for receiving a renewable contact 52 adapted to be engaged by the lower end of a movable contact rod 54, slidably mounted through a substantially central aperture in upper end cap 40.

The arc chamber 42 is preferably subdivided into a plurality of compartments and, as shown, this is accomplished by providing a plurality of disk-like partitions 56 and 58 in insulating tube 44, and a lower partition 60 which forms a relatively small compartment within which contact rod 54 engages renewable contact 52. Partition 60 preferably has the lower surface thereof inclined, as shown at 62, to form the aforesaid relatively small compartment together with end cap 46. The partitions 56, 58 and 60 are maintained in spaced relation within insulating tube 54 by spacer rings 59 and 61, also preferably of insulating material like partitions 56, 58 and 60.

In the operation of the arc chamber thus far described, it will be apparent that when contact rod 54 is moved away from renewable contact 52 and an arc is struck therebetween, and assuming the arc chamber to be filled with an arc extinguishing fluid, such as oil, it will be obvious that the action of the arc on the oil will cause decomposition thereof and create a fluid pressure first within the relatively small chamber between partition 60 and end cap 46. If the arc current is high, this pressure will act on contact rod 54 in a piston-like manner to cause further movement thereof away from renewable contact 52 and draw out the arc successively through the compartments of the arc chamber defined by end cap 46 and partitions 60, 58 and 56. Such large current arcs, therefore, will be exposed successively to an increasingly large arc chamber space, besides being subjected to relatively fresh reservoirs of arc extinguishing fluid maintained in the several compartments. If, on the other hand, the arc current is small, it will not be dissipated throughout a relatively large arc chamber, but, on the other hand, will be confined in the relatively small compartment between partition 60 and end cap 46, to thereby utilize all of this pressure for moving contact rod 54 away from renewable contact 52. Similarly, on arcs of intermediate current value, the pressure developed by these arcs is conserved by the successive relatively small sub-chambers formed within arc chamber 42, so

that the full effect of these pressures is effectively utilized for contact separation.

The upper part of arc chamber 42 is adapted to house a means for biasing contact rod 54 into engagement with renewable contact 52, and to this end a supporting collar 66 is secured to the contact rod 54 as by a pin 68, and a coil tension spring 64 is secured to supporting collar 66 at one end thereof, and the other end thereof is secured to a floating collar 70 freely slidably mounted both with respect to contact rod 54 and insulating tube 44. Spring 64 is preferably secured to supporting collars 66 and 70 by having the end coils thereof seated in peripheral grooves on reduced extensions of the collars. A coil compression spring 72 is provided intermediate spring 64 and the inner wall of insulating tube 44, and is seated at one end on floating collar 70 and at the other end bears against upper end cap 40.

It will be apparent that when contact rod 54 is moved upwardly, it will carry the upper end of tension spring 64 therewith to stress this spring and exert a force on floating spring support 70 to compress spring 72, so that as soon as the force tending to move contact rod 54 away from renewable contact 52 is removed, the springs 64 and 72 will operate to reclose the contacts. By the use of the particular spring arrangement illustrated, it is possible to locate a biasing means capable of exerting a relatively large force for biasing the contacts closed, within a relatively small space, so that the contact closing springs may readily be incorporated as part of the arc chamber 42.

The interrupter chamber 42 is provided with outlet apertures 14 in top cap 40, which are controlled by a pressure and movement responsive valve 76. The valve plate 76 is slidably mounted on contact rod 54, and is provided with a cavity for receiving packing material 78 for frictionally associating the valve plate with contact rod 54. The lower end of the interrupter unit is provided with inlet apertures 82 controlled by check valves 80.

The interrupter unit inlet and outlet passages are provided for the purpose of flushing the unit of used oil and gases provided by the arc following a circuit interrupting operation and supplying the unit with fresh oil from casing 2. In other words, when contact rod 54 is moved away from contact 52 to strike an arc, inlet check valves 80 are forced to seat to close inlet passages 82, and outlet valve plate 76 is carried by contact rod 54 and by the pressure developed within arc chamber 42 into engagement with end cap 40 to close off outlet passages 14 and thereby seal the arc chamber so that pressures developed thereon will act solely to move contact rod 54 outwardly. However, as soon as the circuit is interrupted and contact rod 54 starts its downward movement, it will carry valve plate 76 down with it and open outlet passages 14, whereupon the pressure due to the difference in head of oil between the top of interrupter chamber 42 and the bottom of the chamber will cause inlet check valves 80 to open and permit flow of oil into the arc chamber at the bottom thereof, and outflow of gas and oil out of the top of the chamber. Thus with this arrangement it can be seen that the arc chamber is completely flushed and supplied with fresh arc extinguishing fluid after each circuit interrupting operation. Preferably, casing 2 is filled with arc extinguishing fluid to a level at least above the top of arc chamber 42 so as to retain an adequate

reservoir of arc extinguishing fluid and maintain the pressure required to produce a flow of the fluid through the arc chamber for flushing purposes.

5 Contact rod 54 is connected at the upper end thereof with mechanism designed to move the rod away from contact 52 in response to predetermined electrical conditions an amount at least sufficient to strike an arc between the contacts, with further separation of the contacts being accomplished by the pressures developed in arc chamber 42 as explained above. For this purpose, the upper end of contact rod 54 is pivotally connected as at 85 with one end of a toggle lever 84, and the other end of this toggle lever is pivotally connected as by a pin 87 with one end of a second toggle lever 86, and the other end of toggle lever 86 is pivotally connected as by a pin 88 to a piston rod 90. A piston head 92 is provided at the upper end of piston rod 90 and is adapted to work in a dashpot cylinder 94 integral with top cap casting 28. The upper end of dashpot cylinder 94 is adapted to be closed off by a cover 96 for the top cap casting 28, with the cover being secured to the casting, for example, by screws 98. The casting 28 preferably supports dashpot cylinder 94 by a plurality of radially extending arms 100 to position the cylinder substantially centrally of casting 28, and one of these supporting arms 100 is provided with a passage 102 opening into the cylinder and having a ball check valve 104 controlling the outer end thereof. The valve 104 is normally maintained in a position to close off the outer end of passage 102 by a compression spring 106, with an adjusting screw 108 for adjusting the stress exerted by spring 106. Dashpot 94 is for the purpose of delaying closing action of the circuit breaker contacts, and it will be observed that when the contacts open and piston rod 90 is moved upwardly to move piston head 92 into dashpot cylinder 94, there will be relatively little resistance to this movement because check valve 104 will be unseated against the pressure exerted by spring 106 to permit the escape of fluid from cylinder 94. However, when springs 64 and 72 become operative to reclose the circuit breaker contacts, the check valve 104 will seat on the outer end of passage 102 and prevent the entrance of fluid to the upper end of cylinder 94 so that, in order to move contact rod 54 downwardly, it is necessary that fluid be forced past piston head 92, which has a relatively close fit in cylinder 94 to, therefore, effectively slow down closing movement of the breaker contacts.

Reverting to the toggle between piston rod 90 and contact rod 54 described above, this is utilized for causing initial contact separation an amount at least sufficient to strike an arc between the breaker contacts. As shown in Figs. 2 and 4, toggle pivot pin 87 at the knee of the toggle is extended to one side of the toggle levers into a trackway 110 for guiding the knee of the toggle in a predetermined path. As shown in Figs. 1 to 6 in the normal closed circuit position of the breaker, the toggle is adapted to be positioned substantially at its dead-center position, and is biased by a compression spring 112 to break the toggle to the right, as viewed in Figs. 1 and 3. Compression spring 112 engages between a supporting strip 114 on piston rod 90 and toggle lever 86, at a point adjacent the knee of the toggle. In the normal closed circuit position of the breaker, the toggle is maintained at its dead-center position by a latch lever 116 engaging a

roller 89 on toggle pivot pin 87, and the latch is maintained in engagement with the pin by a coil compression spring 122 engaging between the latch and upper end cap 40 of the arc chamber. Latch 116 is preferably pivotally mounted on an upwardly extending supporting member 120 integral with top cap 40 of the interrupter chamber, for example, as by a pivot pin 118. It will be noted that the trackway groove 110 for pivot pin 87 at the knee of the toggle is provided with a substantially straight vertically arranged portion 126, and a curved side track portion 124 communicating with straight portion 126 intermediate the ends of portion 126 and at the lower end thereof. The communication between the lower end of straight portion 126 of groove 110 and curved portion 124 is unrestricted, whereas the communication of the upper portion of side track 124 with straight portion 126 is controlled by a switch lever 128 pivotally mounted, for example, as at 130 on supporting column 38, and resiliently maintained in a position in which it closes off entrance to side track portion 124, for example, as by a coil tension spring 132 connected between switch lever 128 and a lug on supporting column 38.

In operation, it will be observed that springs 64 and 72 in arc chamber 42 will normally maintain contacts 52 and 54 in engagement; however, when latch lever 116 is depressed to release pivot pin 87 of the toggle, it will be obvious that spring 122 will be operative to cause collapse of the toggle and movement of toggle pivot pin 87 into the curved portion of track 110. Inasmuch as piston rod 90 is prevented from moving downwardly by integral inwardly projecting flange 180 on dashpot cylinder 94, it is obvious that collapse of the toggle and movement of pivot pin 87 into the curved portion 124 of groove 110 will cause some movement of contact rod 54 upwardly out of engagement with respect to renewable contact 52. This will establish an arc between the contacts, and the pressure developed by this arc will cause further upward movement of contact rod 54, and inasmuch as the knee of the toggle is constrained to follow the path of curved portion 124 of groove 110, it will be caused to move through this curved portion and into the upper end of straight portion 126 of the groove while displacing switch lever 128, and thereby cause movement of dashpot piston 92 to the top of cylinder 94 substantially to the position shown in Fig. 5 of the drawings. As soon as the arc is extinguished within arc chamber 42, springs 64 and 72 will be free to move contact rod 54 towards contact 52 to reclose the same, and the toggle pivot pin 87 in its downward movement as restrained by dashpot 94 will be caused to move rectilinearly along the straight portion 126 of slot 110, because switch lever 128 will prevent movement of pin 87 into the curved portion of groove 110, and pivot pin 87 will be reengaged by latch lever 116.

The mechanism for causing release of latch lever 116 to initiate a circuit interrupting operation is supported from supporting column 38. As shown, for example, in Figs. 2 and 4, the upper end of the supporting column 38 is substantially in the form of an inverted U and the short leg 134 thereof is provided with an angularly extending integral extension 136 at one side thereof, for pivotally supporting a plurality of latch release levers 138, 140, 142, respectively, all mounted on a common pivot pin 144. The

release levers are maintained in spaced relation by spacing collars 146 also mounted on pivot pin 144, and these levers are each provided with a coil compression spring 148 engaging the upper side of each lever adjacent pivot 144, and a ledge 149 on the supporting arm 136, to bias the levers in a counterclockwise direction about their pivot 144. A bimetal strip 150 which is of conventional form, being composed of laminations 152 and 154 of materials having different coefficients of expansion, intimately bonded together with the lamination 152 preferably having the higher coefficient of expansion so that upon heating of the strip, the upper unsupported end thereof will deflect to the left, as viewed in Figs. 1, 3, 5 and 6, is adapted to control latch lever 116. The lower end of the bimetal strip is secured, for example, as by rivets 156 to support 120, and is insulated therefrom, for example, as by providing sheets of insulating material 158 on opposite sides of the bimetal strip. An angled supporting bracket 160 is secured to the bimetal strip 150 intermediate the ends thereof, for example, as by rivets 164, and is insulated from the bimetal strip, for example, by the interposed sheets of insulation 162. Bracket 160, as shown in Figs. 1 and 3, normally supports the outer ends of release levers 138, 140 and 142 against the bias exerted by their respective biasing springs 148. The upper end of bimetal strip 150 has secured thereto a latch releasing bracket 166, for example, as by rivets 168, and this bracket is also insulated from the bimetal strip by the interposition of sheets of insulation material 170. Toggle latch lever 116 has secured to the outer end thereof a latch releasing rod 172 having an upper forked end for rotatably mounting a roller 174 adapted to be positioned beneath latch release levers 138, 140 and 142, so as to be engageable by each of the latches when they are released.

The circuit through the breaker extends from a terminal (not shown) on the top cap assembly 26 by way of conductor 176 to the upper end of bimetal strip 150, from the lower end of the bimetal strip by way of flexible conductor 178 to the upper end of contact rod 54. When the contacts are in engagement, the circuit continues through renewable contact 52, end cap 40, coil compression spring 50 to contact bolt 6 and conductor 14. It will be observed that bimetal strip 150 is connected in series with the circuit breaker contacts so that load current flows therethrough, and so that currents above a predetermined value will be operative to heat the bimetal strip and cause deflection thereof in the manner described above.

In the operation of the circuit breaker shown in Figs. 1 to 6 of the drawings, the parts will be disposed in the normally closed circuit position of the breaker, shown in Figs. 1 to 4 of the drawings, with the contacts maintained closed by springs 64 and 72 and with the knee of the toggle comprising levers 84 and 86 latched substantially at dead-center position by latch lever 116, and with latch release levers 138, 140 and 142 all maintained in an inactive position by bimetal strip 150. Upon the passage of currents through the breaker above a predetermined value, bimetal strip 150 will be heated and caused to deflect to the left, for example, to the position shown in Fig. 5 of the drawings, and at this position latch release lever 138 will be released because it is shorter than levers 140 and 142. Upon release of latch release lever 138, it will be

moved in a counter clockwise direction by its biasing spring 148 to cause downward movement of latch release rod 172 and thereby cause clockwise movement of the latch lever 116 out of engagement with toggle pivot pin 87. This will permit the toggle to break to the right, as viewed in Figs. 1 and 3 of the drawings, in the manner described heretofore to separate the contacts and cause movement of the toggle and contact rod together with dashpot piston 92 to the position shown in Fig. 5 of the drawings. It will be noted that in this movement toggle lever 86 is provided with a laterally projecting reset pin 182 which will pick up latch release lever 138 and latch release levers 140 and 142 as well, in the upward movement of the contact, and its associated parts, to raise them to the position shown in Fig. 5 of the drawings wherein levers 138 and 140 may be engaged by latches 184 and 186, respectively. It will be noted that the latch release bracket 166 at the upper end of bimetal strip 150 in the normally closed position of the contacts shown in Figs. 1 and 3, maintains latch levers 184 and 186 in a position in which they are out of the path of movement of pins 188 and 190 provided adjacent the outer ends of latch release levers 138 and 140, respectively. However, as soon as the bimetal strip 150 deflects sufficiently to initiate a first circuit interrupting operation (to the position shown in Fig. 5), the latch levers 184 and 186 are permitted to move downwardly under the influence of gravity to a position where latch lever 184 is engageable with pin 188 on latch release lever 138, to maintain this release lever in the position shown in Fig. 5 even upon reclosure of the circuit breaker contacts.

Accordingly, when the arc is extinguished from the first interrupting operation and springs 64 and 72 reclose the breaker contacts, latch release levers 140 and 142 will be moved into engagement with bracket 160 on the bimetal strip. In the event the overload on the circuit has cleared in the interim, bimetal strip 150 will slowly cool down and gradually resume the position shown in Figs. 1 and 3 of the drawings and eventually engage latch lever 184 causing it to release lever 138 so that the parts will eventually attain their original position shown in Figs. 1 and 3. However, in the event the overload remains on the circuit when the contacts reclose after a first circuit interrupting operation, the bimetal strip 150 will be further deflected, and operate to release the next longest latch release lever 140, to cause release of toggle latch 116 and opening of the circuit in the same manner as before. This time when the contacts open, their latch release levers are moved to the position shown in Fig. 5 by resetting pin 182, and latch 186 will have attained a position wherein it is operative to engage pin 190 on latch lever 140 and maintain this latch release lever as well as latch release lever 138 in an inactive position. As soon as the circuit is interrupted and coil springs 64 and 72 reclose, latch release lever 142 will reengage bracket 160 on the bimetal strip and the circuit will again be reestablished through the breaker. In the event the circuit has cleared on this second successive reclosure, the bimetal strip 150 will again cool down and resume the position shown in Figs. 1 and 3 of the drawings to thereby release latch release levers 138 and 140 to permit all the parts to resume their positions shown in Figs 1 to 4. However, in the event the overload has not cleared after the second successive re-

closure of the breaker contacts, the bimetal 150 will further deflect to the position shown in Fig. 6 of the drawings and release the last and longest latch release lever 142 to cause movement of latch 116 to release toggle pin 87, whereupon the contacts will be opened as before. However, there is no latch for maintaining latch release lever 142 in an inactive position so that when springs 64 and 72 attempt to reclose the breaker contacts a third time, latch release lever 142 will drop to its lowermost position defined by an angular extension 194 of a reset lever 192 pivotally mounted on bracket support 136, and in this position an integral lug 197 on the upper side of latch release lever 142 will be positioned in the path of a lockout pin 199 integral with piston rod 90 to prevent downward movement of the piston thereof and consequently prevent reengagement of the breaker contacts. Lug 197 extends from the upper side of lever 142 laterally at an angle into the path of movement of pin 199 as shown in Fig. 4. Pin 199 has a slabbed off side to normally provide clearance with lug 197. Resetting lever 192 is provided with an angularly extending portion 195 adapted to extend through an aperture in cover casing 28 and outer cover 201 to provide a visible indication of the condition of the circuit breaker. In order to reset the breaker contacts after they have become automatically locked open in response to three successive circuit interrupting operations, it is merely necessary to depress the outer end 196 of the lever to cause rotation of the lever in a clockwise direction and raise latch release lever 142 from the position shown in Fig. 6 until lug 197 thereon is moved out of the path of downward movement of lockout pin 199, whereupon springs 64 and 72 are free to reclose the breaker contacts. Upward movement of latch release lever will reseat the outer end of this lever on bracket 160 of the bimetal strip, and, of course, cooling down of the strip will have released latches 184 and 186 to reset latch release levers 138 and 140 so that the parts will resume their positions shown in Figs. 1 to 4 of the drawings in readiness for the next overload that comes on the circuit.

Of course, each reclosure of the circuit breaker contacts is delayed by the action of dashpot 94 to permit the fault on the circuit to clear if it is of the self-clearing type, and also allow sufficient time for flushing of interrupter unit 42 prior to reclosure of the breaker contacts. It will be noted that extension 194 of reset lever 192 extends beneath latch levers 138 and 140 as well as latch lever 142, to insure resetting of all the latch levers when the outer end 196 of the reset lever is depressed.

In Fig. 7 of the drawings, there is illustrated a circuit breaker having many parts like those of the breaker shown in Figs. 1 to 6 of the drawings and, accordingly, like reference numerals will be used to designate like parts in order to avoid undue repetition and to clarify the description of the distinctive parts thereof. In the breaker shown in Fig. 7, the arc chamber 42 is preferably so related to insulating casing 2 as to substantially fill the casing, with most of the operating mechanism contained in a hollow casting cover structure 204, and instead of utilizing a toggle for slightly separating the breaker contacts in response to predetermined electrical conditions as in the embodiment of Figs. 1 to 6, lower end cap 46 for the arc chamber is provided with a relatively large central aperture, and serves to clamp between the end cap and partition 60, a

bimetallic disk 198 which is concavo-convex in form. Bimetal disk 198 may be of any well known type having laminations of different coefficients of expansion so that when the disk is heated, stresses will be set up therein tending to reverse the curvature thereof, and this will take place with a snap action in a manner well known in the art. The central portion of bimetal disk 198 is apertured for receiving the stem of a combined contact and valve member 200 having an outer head 202, provided for limited sliding movement of the stem thereof with respect to bimetal disk 198.

The cover construction 204 includes a cylindrical casing 205 with a bottom plate 203 secured to the lower end thereof and adapted to seat on the upper end of insulating casing 2, and to have top cap 40' of the interrupter chamber secured thereto, for example, as by bolts 209. Cover casing 205 is, like casing 28 in the embodiment of the invention shown in Figs. 1 to 6 of the drawings, provided with a dashpot cylinder 94 for receiving a piston head 92 mounted on a piston rod 195 integral with contact rod 54. The upper end of dashpot cylinder 94 and the upper end of cover casing 205 are closed like cover casing 28 shown in Figs. 1 to 6, with a cover 96 secured thereto in any desired manner. Cover assembly 204 is preferably provided with a second dashpot cylinder 206 having a closed upper end pivotally mounted as at 208 on a supporting bracket 210 integral with cover casing 205. Dashpot cylinder 206 is preferably provided adjacent the closed end thereof with a check valve 207 permitting flow of fluid outwardly of the casing but not inwardly, and the side wall of dashpot cylinder 206 adjacent the open end thereof is preferably provided with an open vent 211 for a purpose to be hereinafter described. Dashpot cylinder 206 is preferably biased by a coil spring 212 disposed about pivot 208, for movement in a generally clockwise direction about its pivot. A piston rod 214 having a head 216 for reception within dashpot cylinder 206, is preferably biased outwardly with respect to the dashpot cylinder by a coil compression spring 213 engaging the piston head 216 and the bottom of dashpot cylinder 206. The outer end of piston rod 214 is provided with a notch 218 adapted to receive the transverse end portion 220 of a cross bar 222 secured to piston rod 195. A fixed abutment 224 may be formed integral with cylindrical casing 205 of the cover assembly, and this abutment includes a vertically extending upper surface 226 and an offset vertically extending lower surface 230, connected by an inclined intermediate surface 228 adapted to form a track for rollers 232 (only one shown) at opposite sides of rod 214, and mounted on a pin 234 provided on piston rod 214.

The circuit through the breaker shown in Fig. 7 preferably extends from a terminal (not shown) on hollow cover assembly 204, through a flexible conductor 233 to piston rod 195, contact rod 54, contact 200 to the center of bimetal disk 198, thence to the outer edges of disk 198, lower cap 46', compression spring 50 and contact bolt 6. Therefore, it will be seen that bimetal disk 198 is connected in series through the breaker constituting this embodiment of the invention, so as to be responsive to the passage of currents through the circuit above a predetermined value to reverse the curvature thereof.

In the operation of the breaker shown in Fig. 7, and assuming the parts to be in the normal

closed circuit position shown on the drawings, upon the passage of overload currents therethrough bimetal disk 198 will be heated to reverse the curvature thereof and move contact 5 200 out of engagement with the lower end of contact rod 54 and draw an arc therebetween. The pressure developed within arc chamber 42 will cause movement of contact rod 54 away from contact 200 in the same manner as in the embodiment of Figs. 1 to 6. However, this upward movement of contact rod 54 will also cause movement of piston 216 into dashpot cylinder 206. As soon as the arc is extinguished, springs 64 and 72 will cause reclosure of the breaker contacts, as explained in connection with the previously described embodiment of the invention, with this reclosure, of course, being delayed by the action of dashpot cylinder 94. Dashpot spring 213 is preferably relatively weak so that it will move its piston 216 outwardly of dashpot cylinder 206 a great deal slower than piston 92 is moved outwardly of dashpot cylinder 94. As soon as contact rod 54 moves towards contact 200, cross bar 222 will become disengaged from piston rod 214 and thereby permit spring 212 to rotate dashpot cylinder 206 in a clockwise direction about its pivot 208 until rollers 232 on piston rod 214 engage the surface 226 of abutment 224. When the breaker contacts are reclosed by downward movement of contact rod 54 and return of bimetal disk 198 to the position shown in Fig. 7, and assuming that the overload condition on the circuit has been removed, dashpot piston 216 will continue to be slowly moved 30 downwardly by spring 213 with its roller successively moving along surfaces 226, 228 and 230 of abutment 224. As rollers 232 move along inclined surface 228 of abutment 224, one of the rollers will engage a lateral flange 240 on the upper end of a lockout lever 236 pivotally mounted on bottom plate 203, to move this lever in a clockwise direction about its pivot until this roller 232 moves from under the lower end of flange 240, whereupon the lockout lever will 40 be returned to the position shown in Fig. 7 by a coil spring 227 located at its pivot. However, if the overload condition has not been removed from the circuit, then after the contacts have reclosed, bimetal disk 198 will again reverse its 45 curvature to strike an arc and cause a circuit interrupting operation as before. By this time, dashpot piston 216 will only be about halfway out of dashpot cylinder 206 and roller 232 will be substantially at the dotted line position shown 50 in Fig. 7. Accordingly, contact rod 54 and piston rod 195 with piston 92 are free to move upwardly and then reclose the circuit after interruption takes place without affecting dashpot cylinder 206 or piston 216. If the overload condition has been removed, after the second 55 reclosure, dashpot piston 216 will continue to move out of cylinder 206 and rollers 232 will move along the surfaces of abutment 224 as before, to reset notch 218 thereof in engagement with transverse end 220 of cross bar 222, as shown 60 in Fig. 7. However, if the fault still has not cleared upon the second reclosure, operation of the breaker bimetal disk 198 will again cause a circuit interrupting operation, and this will 65 again take place without affecting dashpot piston 216. However, upon attempted reclosure this time, one roller 232 on dashpot piston rod 214 will have engaged flange 240 on lever 236 to move this lever in a clockwise direction about its pivot so that the notch 238 in the upper end 70 75

thereof is in the path of downward movement of transverse end 220 of cross bar 222, to thereby prevent reclosure of the contact.

To reset the breaker to normal operating condition following an automatic lockout operation of the contacts, a link 235 is pivoted to the end of cross bar 222 opposite transverse portion 220, and to a manually operable lever 237 extending through an aperture in cover assembly 204, so that the cross bar 222 may be manually moved upwardly to permit roller 232 to pass from beneath flange 240 on lockout lever 236, so that the lever may resume its normal position shown in Fig. 7, whereupon by release of lever 237 the breaker contacts will be closed by springs 64 and 72 as before.

The vent 211 in the side of dashpot cylinder 206 is provided so that after roller 232 passes from beneath flange 240 on the lockout lever 236, movement of dashpot piston 216 and piston rod 214 will take place rapidly until the movement is halted by engagement of notch 218 with end portion 220 of cross bar 222. Arc chamber 42 in this embodiment of the invention is flushed out after each circuit interrupting operation by providing an outlet passage 241 extending longitudinally of contact rod 54 and which is opened as soon as the upper end of the passage enters the cover assembly 204 to permit the escape of gas and fluid from the upper end of the arc chamber, and gravity flow is obtained into the lower end of the arc chamber by the check valve action of contact 200. It will be observed that the lockout action in this embodiment of the invention is dependent upon the lapse of a time predetermined by the characteristics of dashpot 206, and is not dependent upon any particular number of successive operations as in the embodiment described in connection with Figs. 1 to 6 of the drawings. Also, in this embodiment of the invention the contacts are first separated to establish an arc to provide for further contact separation by pressures developed by the arc struck by a bimetal disk, rather than by the toggle arrangement shown in Figs. 1 to 6.

In Fig. 8 of the drawings there is shown a slightly modified form of arc chamber and contact construction somewhat along the lines of the embodiment shown in Fig. 7, but with a different contact separating means. In this embodiment of the invention, the insulating casing 2 is provided with a contact bolt 244 through a central aperture in the closed bottom of the casing and secured in position, for example, by nuts 246. Beneath the head of bolt 244 there is provided a leaf spring 248 for contact with the lower terminal plate of the breaker assembly. The insulating tube 44 for the interrupter chamber is provided adjacent the lower end thereof with spaced sleeves 252 for positioning a partition disk 250 similar to the disks 56 and 58 of the first described embodiment of the invention, and a contact block 256 of conducting material such, for example, as copper or the like, is maintained in position at the lower end of tube 44 by a lower terminal cap 254 threadedly engaging the lower end of tube 44. The conducting block 256 is provided with a central bore 258 of less diameter than that of contact rod 54 so that the rod may engage the top of contact block 256 and close the top of bore 258. Cap 254 is provided with a central cylindrical bore 262 adapted to receive a piston-like contact 266, which is slidably mounted therein. The upper portions of the walls of cylindrical bore 262 are

preferably provided with peripherally spaced grooves 264 adapted to be aligned with radial grooves in the lower surface of contact block 256 for a purpose to be hereinafter described.

- 5 The lower cap 254 for the arc chamber supports a contact plate 268 by means insulating spacing and supporting means 265, and plate 268 is adapted to pivotally support an insulating toggle lever 270 at one end thereof, with
- 10 the other end of the lever pivotally connected to one end of a toggle lever 272, and the other end of this lever being pivotally connected to contact piston 266. Each of the toggle levers is provided with an integral lateral extension, with
- 15 toggle lever 270 having the lateral extension 274, and toggle lever 272 having a shorter lateral extension 276 with a pivoted catch 278 at the outer end thereof biased in a counterclockwise direction with respect to extension 276 by a
- 20 spring 280 coiled about its pivot, into engagement with a stop lug 282 integral with extension 276. A coil spring 284 is coiled about the supporting pivot for toggle lever 270 and disposed to bias this lever for movement in a counterclockwise direction about its supporting pivot to break the toggle to the left, as viewed in Fig. 8, from its normal position adjacent dead center.
- 25 A bimetal strip 286 is insulatedly supported at its upper end on end cap 254, and is provided with a projection 288 at its lower end for engagement with pivoted catch 278 on toggle lever 272, to restrain the toggle from movement under the influence of biasing spring 284.

A flexible bellows 290 is adapted to be supported on contact plate 268 and is adapted to be filled with a fluid capable of uniform expansion upon being heated within a predetermined range, such, for example, as chlorinated diphenyl, and a resistance heating element 292 is positioned

- 30 within the bellows for heating the fluid to obtain expansion of the bellows. The upper end of the bellows is provided with an actuating projection 294 having an angular extension 296 positioned to be engaged by the lower end of bimetal strip 286 when in its normal position shown in Fig. 8.

The circuit through the interrupter shown in Fig. 8 extends from conductor 298 which may be connected to a terminal on the top cover assembly for casing 2, through a main circuit when

- 35 the breaker contacts are closed, by way of conductor 300 to contact rod 54, conducting block 256, contact piston 266, toggle link 272, flexible conductor 302 to the upper end of bimetal strip 286, through the bimetal strip, conductor 305 to
- 40 contact plate 268 which is engaged by leaf spring 248 and completes the circuit to terminal bolt 244. An auxiliary contact closing circuit extends from conductor 298, through conductor 304 to one terminal of bellows heater 292, through the heater to angular extension 296 on the bellows actuator, to the lower end of bimetal strip 286, and conductor 305 to terminal bolt 244.

In the operation of this embodiment of the invention, it will be observed that since bimetal strip 286 is in series in the main current path through the interrupter, it will be deflected to the left upon heating of the strip by currents above a predetermined value to release the outer end of pivoted toggle lever 278 and permit the toggle to be broken to the left by biasing spring 284, to thereby draw contact piston 266 downwardly out of engagement with contact block 256 and draw an arc therebetween. Downward movement of contact piston 266 is limited by engagement of toggle lever extension 274 with bellows

290 so that the contact piston will not leave the cylindrical bore 262 in end cap 254, but will move downwardly sufficiently to close off grooves 264 and seal the lower end of the arc chamber. The arc thus drawn will establish pressure within the chamber, as before, and cause movement of contact rod 54 upwardly to interrupt the circuit. Any desired type of reclosing and lockout means may be associated with contact rod 54, such, for example, as the mechanism shown in Fig. 7 of the drawings. In any event when contact rod 54 is moved downwardly into engagement with contact block 256 after the circuit has been interrupted, the circuit through the breaker will not be reclosed until bimetal strip 286 has cooled down sufficiently to deflect back substantially to its original position shown in Fig. 8 wherein it engages extension 296 of bellows actuator element 294 to complete the circuit through the bellows heating element 292. All of the current will then flow through this circuit, inasmuch as the main circuit through contact rod 54 and contact piston 266 is still open, and this will cause heating of resistor 292 to heat the fluid within the bellows and cause expansion thereof and engagement of actuator 294 with extension 274 of toggle lever 270 to move the toggle towards its dead-center position, and relatch pivoted extension 278 beneath catch 288 on bimetal strip 286. The extension 278 is pivoted with respect to toggle lever 272 in order to permit deflection of the lever to pass catch 288 on the bimetal strip during its resetting movement. Of course, as soon as the toggle is reset in the position shown in Fig. 8, contact piston 266 will reengage contact block 256 to reestablish the main circuit through these contacts, and since this main circuit contains less resistance than that of the shunt circuit through bellows heater 292, the main current path will flow through this main circuit and through bimetal 286 so that the breaker is restored to a condition wherein it is again ready to interrupt the circuit in the event of the occurrence of current above a predetermined value.

In this embodiment of the invention, contact separation and final reclosure are both under the control of electroresponsive means, that is, a bimetal strip and electrically heated bellows respectively, and the time delay for reclosure of the breaker contacts is obtained by the cooling down of the bimetal strip rather than by a dashpot 94 as in the previously described embodiments. From the foregoing, it will follow that if the lockout and reclosing spring means shown in Fig. 7 are utilized with the construction shown in Fig. 8 of the drawings, dashpot 94 for delaying closing movement of the contact rod 54 may be entirely eliminated since this function is taken over by bimetal strip 286 as described above. The upper end of the interrupter unit is preferably vented by contact rod passage 241 as in Fig. 7, and fresh oil may flow into the bottom of the unit through grooves 264 as contact piston 266 is closed.

In Fig. 9 of the drawings, there is illustrated a means for securing initial contact separation somewhat similar to that shown in Fig. 8, and for use with reclosing and lockout means, for example, like that shown in Fig. 7, but in this embodiment of the invention a bellows arrangement is utilized for securing initial separation, and reclosure of the contacts is obtained by a spring. Inasmuch as many of the parts of this embodiment of the invention are identical with those of previously described embodiments, like refer-

ence numerals will be used to designate like parts and the description of these parts will not be repeated in detail.

The insulating tube 44 for the arcing chamber 5 is provided with a lower end cap 306, and the end cap is provided with a central aperture for receiving a contact piston rod 308 pivotally connected at its lower end to an operating lever 310, for example, as by a pivot pin 312 engaging in a slot 313 in operating lever 310. One end of the operating lever 310 is pivotally mounted as at 314 on an upwardly extending support 316 integral with the lower leg 318 of an L-shaped bracket formed on lower end cap 306, and a coil 15 compression spring 320 is positioned between the other end of the actuating lever and leg 318 of the supporting bracket, for biasing the actuating lever in a counterclockwise direction, about its pivot 314 to move contact piston rod 308 upwardly into engagement with contact rod 54. A stop lug 322 is provided integral with the L-shaped supporting bracket for limiting upward movement of actuating lever 310. Cap 306 is provided with spaced apertures for inlet check 20 valves 324 similar to those previously described in connection with the embodiment of the invention shown in Figs. 1 to 6 of the drawings. A bellows 326 similar to the bellows 290 previously described, is provided with a resistor 328 and this is connected in the circuit through the interrupter by a flexible conductor 330 connected to contact piston 308, and by a conductor 332 connected to an insulated contact rivet 334 extending through an aperture in leg 318 of the 25 supporting bracket, and insulated therefrom by an insulating collar 336, to engage head 338 of terminal bolt 340.

In the operation of this embodiment of the invention, it is obvious that the passage of currents 40 above a predetermined value through the breaker will cause sufficient heating of bellows resistor 328 as to expand the bellows to cause engagement of the actuating projection 342 thereof with an integral lug 344 on actuating lever 310. Continued expansion of the bellows will produce downward movement of actuating lever 310 and withdraw contact piston 308 from engagement with contact rod 54 to establish an arc. This will cause movement of contact rod 54 upwardly to 45 increase the contact separation in the manner previously described, and as soon as the circuit has been interrupted, biasing spring 320 will be effective to move contact piston 308 upwardly to the position shown in Fig. 9 and a biasing means 50 such, for example, as springs 64 and 72 shown in the embodiments of the invention of Figs. 1 to 7 of the drawings will be free to restore contact rod 54 into engagement therewith. The bellows arrangement for separating the contact 55 shown in Fig. 9 will give a time delay in interrupting a circuit somewhat greater than that of the bimetal strip or disks utilized in the embodiments of the invention previously described.

The embodiment of the invention shown in 60 Fig. 10 of the drawings is quite similar to that shown in Figs. 7 and 9, but utilizes a modified form of contact opening and lockout means. In this embodiment of the invention, the contact rod 54 is extended up out of arc casing 42 and 65 has a piston head 346 directly mounted thereon for cooperation in dashpot cylinder 348, which, like dashpot cylinder 94 previously described, is adapted to be formed integrally with a casing cover. Contact rod 54 in this embodiment of the 70 invention is electrically connected with cover 96

for the cover assembly by a conductor 384 secured to the cover, and to dashpot piston 346.

The lower end of interrupter chamber 42 is provided with a bottom cap fixture 350 similar to that shown in Fig. 9, in that it is provided with inlet check valves 382 and a central opening for a contact piston 352 adapted to be actuated by an insulating toggle link 354 pivotally connected thereto as at 356, and a second toggle link 360 pivotally connected to link 354 by pivot pin 358 and, in turn, mounted on one leg 364 of an L-shaped supporting bracket integral with bottom cap 350 by a pivot pin 362. A helically wound coiled bimetal element 368 is adapted to be connected between the other leg 366 of the L-shaped supporting bracket, and pivot pin 358 at the knee of the toggle formed by levers 354 and 360, to control movement of the toggle. Bimetal coil 368 is supported on leg 366 of the L-shaped bracket by an insulating supporting bracket 370, and a bimetal strip 372 is also adapted to be supported at one end on insulating bracket 370, and has the other end thereof hook shaped, as at 374, for cooperation with a catch 374 on toggle lever 360.

Normally, the toggle formed by levers 354 and 360 is maintained by bimetal coil 368 at a position slightly to the left of its dead center position, as viewed in Fig. 10, and against a stop lug 376 integral with leg 364 of the supporting bracket.

The circuit through the interrupter shown in Fig. 10 extends from the top cover structure through conductor 384, contact rod 54, contact piston 352, flexible conductor 386, bimetal coil 368, flexible conductor 388, bimetal strip 372 to terminal conductor 390. The coiled helically wound bimetal 368 is of a type well-known in the art which, when heated, will act to contract to move the knee pivot 358 of the toggle to the right, as viewed in Fig. 10, and conversely when cooled down, bimetal coil 368 will act to move the knee of the toggle in the opposite direction.

Inasmuch as both bimetal coil 368 and bimetal strip 372 are connected in series in the circuit through the interrupter of Fig. 10, they will both be heated by currents passing through the interrupter in excess of a predetermined value. Bimetal strip 372 is of conventional construction comprising laminations of materials having different coefficients of expansion with the material of greater coefficient located at the upper side of the strip so that upon heating, the outer end of the strip will be deflected downwardly to engage lug 374. Bimetal strip 372 should be correlated with respect to bimetal coil 368 so that repeated heatings of the strip are required to bring the hooked end 374 thereof into the path of movement of lug 374, whereas a single heating of coil 368 will suffice to move the toggle knee pivot 358 to the right an amount sufficient to withdraw contact piston 352 from contact 54 and establish an arc therebetween. Thereupon contact rod 54 will be moved upwardly to interrupt the circuit by the pressure generated in arc chamber 42 by the arc, and when the circuit has been interrupted, springs 64 and 72 will return contact rod 54 delayed by the action of dashpot cylinder 348, substantially in the same manner as described in connection with previous embodiments of the invention. As stated above, bimetal strip 372 will also be heated, but it will not be heated an amount sufficient to bring the hooked end 374 thereof into the path of movement of lug 374 when it is moved to the right, as viewed

in Fig. 10, by bimetal coil 368. The circuit will be reclosed upon cooling of bimetal coil 368 an amount sufficient to return the toggle and contact piston 352 to the position shown in Fig. 10. However, because of the heating characteristics of bimetal strip 372, this will not have cooled sufficiently to attain its original position shown in Fig. 10 by the time the circuit is reclosed.

Now if the overload condition on the circuit has been cleared after this first reclosure of the contacts, the bimetal strip 372 will merely continue to cool down until it resumes its position shown in Fig. 10, and the parts will be ready for the next overload condition which occurs. However, if the overload remains on the circuit after the first reclosing operation, a circuit interrupting operation is again initiated by bimetal coil 368 and carried through, as before, and this time bimetal strip 372 has the outer end thereof, 374, deflected downwardly a greater distance than the first time. The circuit is reclosed after the second successive interrupting operation as before, and if the fault has cleared on this reclosure, the bimetal strip 372 will eventually resume its original position shown in Fig. 10. If the fault has not cleared on the second reclosure, the circuit is again opened and this time bimetal strip 372 is heated a further amount sufficient to bring the hooked end 374 thereof into the path of movement of lug 374 when moved to the right in the circuit interrupting operation, to thereby become engaged by hook 374 and prevent movement of toggle knee pivot 358 to the left by bimetal coil 368 when it cools down, thereby locking the breaker contacts in their open circuit position. The upper end of lug 374 is inclined with respect to the vertical away from bimetal strip 372, and the hook 374 on the strip is similarly inclined so that cooling of strip 372 will not exert sufficient force to disengage these parts.

After the breaker contacts have been locked open, they may be reset only by a manual operation, and to this end manually operable reset rod 378 is provided which may extend through the breaker cover assembly, and it has an angularly extending lower end 380 extending into proximity below bimetal strip 372, to exert sufficient force on the bimetal strip when rod 378 is moved upwardly, to disengage the hook end 374 thereof from lug 374 on toggle lever 360. This will obviously permit bimetal coil 368 to move the toggle to the left and reset the circuit breaker contacts in engagement.

In Fig. 11 of the drawings, there is shown a modified form of operating mechanism and lock-out means for a circuit breaker, and this mechanism has been shown as applied specifically to a breaker having an operating rod construction, and which may also have an arc chamber construction like that illustrated in Figs. 1 to 6 of the drawings. Since many of the parts shown in Fig. 11 are identical with those illustrated in the first described embodiment of the invention, like reference numerals are used to designate these like parts. In this embodiment of the invention, a toggle is provided connected to the upper end of contact rod 54 as in the embodiment of Figs. 1 to 6, and at the upper end of the toggle a piston rod 392 is provided which carries piston head 92, and slidably passes through an apertured lug 394 on supporting column 395 depending from the cover structure. A latch lever 398 similar to the latch lever 116 in the first described embodiment of the invention, is pivotally mounted as at 400 on the supporting frame for engaging

the toggle pivot 87, to normally maintain the toggle adjacent its dead center position. An upwardly projecting support 402 on a flange of supporting column 395 is adapted to pivotally support an actuating cam wheel 404, which is provided with a shaft 406 pivotally mounted on support 402. The wheel 404 is provided with stop projections 408, 410 and 412 which project from the periphery of the wheel at progressively greater distances from the center of the wheel, respectively. Actuating projections 413, 414 and 415 are also provided on the periphery of wheel 404, and these projections preferably are located at the same radii with respect to the center of the wheel and are spaced angularly the same amount as stop projections 408, 410 and 412. A coil tension spring 416 is connected between a pin 417 on wheel 404 and an integral apertured lug 419 on the supporting base, to normally bias wheel 404 in a clockwise direction about its pivot axis 406. Movement of the wheel under the influence of spring 416 is normally prevented by a bimetal strip 418 mounted on an integral projection 420 on the supporting base, and insulated therefrom, for example, as by a strip of insulating material 422. The upper end of bimetal strip 418 is provided with an insulating stop projection 424 secured thereto, and adapted to engage stop projections 408, 410 and 412, and in the normal position of the breaker it will be in engagement with stop projection 408, as shown in Fig. 11. Actuating projections 413, 414 and 415 on wheel 404 are adapted to engage and actuate an actuating rod 426 integral with latch lever 398, and this rod is provided with an integral lug 428 against which one end of a coil compression spring 430 is adapted to seat, with the other end of the spring seated on the supporting flange integral with the supporting column 395. This spring 430 will obviously bias latch 398 into engagement with toggle pivot pin 87. A lateral extension 432 of support 402 is provided for supporting a bracket 434 having spaced apertured flanges for slidably receiving a lockout pin 436, which, in turn, has a flange 440 acted on by compression spring 438, to normally maintain the pin against the surface of a cam 442 fixed on shaft 406, so as to be movable with actuating wheel 404.

It will be noted that there is provided a second dashpot cylinder 444 preferably formed integral with the cylinder 94 for receiving a piston 446 on a piston rod 448 slidably mounted in the aperture of lug 396. A coil compression spring 450 is provided in dashpot cylinder 444 for normally biasing piston 446 outwardly, and a check valve controlled outlet 445 is provided in the upper end of the cylinder to permit the passage of fluid out of the cylinder, but to close off this passage when fluid attempts to enter. Adjacent the lower end of dashpot cylinder 444 there is provided a further aperture 452 for a purpose to be herein-after described. The lower end of dashpot piston rod 448 is provided with an integral resetting lug 453 which is adapted under certain conditions to engage a resetting lever 462, pivotally mounted on support extension 432, and having the opposite end 464 thereof engageable with pin 417 on actuating wheel 404. Piston rod 448 also extends into the path of movement of an integral actuating lug provided on piston rod 392, so that dashpot piston 446 is moved to the top of its stroke every time the contacts are opened. The outer end of actuating lug 454 on piston rod 392, is provided with a pivoted catch 456 which is nor-

mally biased by a compression spring 458 into engagement with a stop lug 460, integral with lug 454.

The circuit through the interrupter shown in Fig. 11 is adapted to extend through a flexible conductor 466 which may be connected to the upper end of bimetal strip 418, through the strip and flexible conductor 468 to the upper end of contact rod 54. This obviously provides bimetal strip 418 in a series circuit through the interrupter so that the strip will be responsive to currents above a predetermined value to deflect the upper end thereof to the left, as viewed in Fig. 11, and release operating wheel 404 for movement under the influence of its biasing spring 416.

When the wheel 404 is released for movement by deflection of bimetal strip 418, actuating projection 415 will move rod 426 downwardly, and thereby release latch 398 from toggle pivot pin 87 and permit the toggle to break to the right and interrupt the circuit in a manner previously described in connection with the embodiment of the invention shown in Figs. 1 to 6 of the drawings. When the contact rod 54 moves upwardly in the circuit interrupting operation, piston rod 392 will also be moved upwardly and this will, in turn, cause lug 454 integral therewith to move dashpot piston 446 to the upper limit of its travel. After the circuit has been interrupted, it will be reclosed as in the first described embodiment of the invention with the reclosing action delayed, of course, by dashpot cylinder 94. Dashpot cylinders 94 and 444 have different characteristics, in that the cylinder 444 and its piston will have a considerably longer time delay than that of cylinder 94, so that when the contacts are reclosed after an interrupting operation dashpot piston 446 will have been moved by spring 450 only a fraction of its travel out of cylinder 444. Actuating wheel 404 after stop lugs 408 has been released by deflection of the bimetal strip, will move only the distance from stop lug 408 to lug 410, and the latter lug will engage projection 424 on the bimetal, because it is a greater distance from the center of the wheel than projection 408.

Now, in the event that the circuit has been cleared after the first reclosing operation, the contacts will remain closed and dashpot piston 446 will slowly move out of cylinder 444 until resetting lug 453 on piston rod 448 engages resetting lever 462 to rotate actuating wheel 404 in a counterclockwise direction and reset projection 408 on the bimetal catch 424. However, in the event the overload has not cleared after the first reclosing operation, the bimetal 418 will be deflected further to release projection 410 and permit movement of the wheel a distance corresponding to that between projections 410 and 412, where its movement will again be arrested by catch 424 on the bimetal, and this will cause actuating projection 414 on the wheel to engage rod 426 on latch 398, to release the toggle pivot pin 87 and cause another circuit interrupting operation. This time the circuit will be interrupted as before and reclosed, and at the time of this second reclosure dashpot piston 446 will be, for example, about two-thirds of the way out of cylinder 444. Again, if the circuit is cleared on the second reclosure, dashpot piston 446 will continue out of cylinder 444 and finally reset actuating wheel 404 to the position shown in Fig. 11. However, if the circuit is not cleared after the second reclosure, bimetal 418 deflects still further and releases lug 412 so that actuat-

ing projection 413 releases latch 398 to cause a third interrupting operation as before, but this time cam 442 which moves with wheel 404 will project lockout pin 436 into the path of movement of the pivoted catch 456 on dashpot piston rod 392, so that in any attempted reclosure of the circuit breaker contacts, contact rod 54 will be prevented from moving downwardly to reengage the other breaker contact.

After the breaker shown in Fig. 11 has been automatically locked in an open circuit position, as described above, dashpot piston 446 will continue its movement outwardly of cylinder 444 and finally will engage reset lever 462 to reset actuating wheel 404 an amount sufficient to reset lug 412 in engagement with bimetal stop 424. This will move cam 442 out of engagement with pin 46. However, this will not affect the condition of the circuit breaker, and it will remain locked open until a manually operable actuating lever 474 is raised to lift piston rod 392 by means of a connecting link 472 connected to a lug 470 integral with the piston rod. This lifting action of the piston rod will remove pivoted catch 456 from lockout pin 436, and permit the pin to be retracted by spring 438, so that when manual actuating lever 474 is released, the contacts will be reclosed in the normal manner. If no overload is present on the circuit on this reclosure, piston 446 will descend and reset actuating wheel 404 to the position shown in Fig. 11. It should be noted that the vent 452 in dashpot cylinder 444 permits a rapid final resetting movement of dashpot piston 452 in resetting actuating wheel 404.

In Fig. 12 of the drawings there is illustrated a circuit breaker very similar to that shown in Fig. 7 of the drawings with the addition to the structure of Fig. 7, of certain controls to insure positive separation of the breaker contacts on an interrupting operation in response to relatively low overload currents. Inasmuch as most of the parts of this breaker are identical with that of the breaker illustrated in Fig. 7, like reference numerals will be used here to designate like parts. As shown in Fig. 12, an actuating rod 476 is connected to reset lever 237 by a pin and slot connection 478, and the lower end of this rod is adapted to be connected to an actuating pin 479 on the actuating projection 480 of a bellows 482. This bellows may be of the same type previously disclosed in connection with Figs. 8 and 9 of the drawings, and includes a resistance heating element 483. Normally, the actuating projection 480 of the bellows is latched in the position shown in Fig. 12 by a spring pressed detent 484 engageable in a peripheral groove 485, near the outer end of projection 480. Detent 484 is constructed to permit expansion of the bellows upon the exertion of sufficient force to cam the detent out of groove 485 against the bias of the detent spring.

The bellows 482 is connected in a shunt circuit through the breaker in the following manner. One terminal conductor 486 of the breaker extends through an insulating bushing in the cover assembly, and the main circuit through the breaker continues to the lower end of a bimetal strip 488, insulatingly supported on a bottom plate 203 of the cover assembly as at 490, through the bimetal strip to a pivoted contact lever 492, contact 496, flexible conductor 502 to dashpot piston rod 195 and contact rod 54, contact 200, bimetal 198, spring 50 to the head 8 of terminal bolt 6. Pivoted contact lever 492 is

adapted to be pivotally supported on a bracket 498 insulated from the cover assembly by insulation 500, and the contact lug 494 thereon is adapted to engage a fixed contact 496 also supported on bracket 498 when contact lever 492 is maintained in the position shown, by bimetal strip 488.

One terminal of heating element 483 of the bellows is connected to terminal conductor 486 by a conductor 504, and the other terminal of the heating conductor is connected to the fixed contact 496 so that the heating element is in a high resistance shunt circuit with respect to the main current path through the breaker.

- 10 15 Bimetal strip 488 is preferably correlated with respect to bimetal disk 198 so as to deflect together to separate contact 200 from contact rod 54 at the same time bimetal strip 488 releases contact lever 492. Accordingly, assuming that 20 the bimetal strip and disk are deflected by relatively high currents, an arc will be struck between contact rod 54 and contact 200 which, because of the high current value thereof, will immediately generate sufficient pressure to separate 25 the contacts and extinguish the arc before heating element 483 of the bellows has had an opportunity to become heated sufficiently to cause expansion of the bellows. However, in the event that the current interrupted is of a relatively 30 low value, so that the arc formed between contact rod 54 and contact 200 is incapable of generating sufficient pressure in the arc chamber to cause enough separation of the contacts to extinguish the arc, after the main circuit has been 35 opened by deflection of bimetal strip 488 so that the circuit then passes through the heating element 483 of the bellows, this will gradually heat up and cause expansion of the fluid within the bellows to exert a stress on operating projection 480 which finally will overcome the holding force 40 of detent 484, and raises actuating lever 476 and consequently piston rod 195 and contact rod 54 through lever 237 and connecting link 235, with a quick action because of the forces stored to 45 overcome the action of detent 484, and thereby positively separates the breaker contacts to interrupt the circuit on such low current operation. It will be noted that each time contact rod 54 moves upwardly and carries cross arms 222 50 therewith, a resetting pin 489 on connecting link 235 will engage contact lever 492 to reset the same in engagement in the upper end of bimetal 488. Accordingly, in this embodiment of the invention provision is made for positively insuring 55 interruption of the circuit on either high or low current operation, with the high current operation being accomplished primarily by fluid pressure generated in the arc chamber by the arc itself, and when the current interrupted is so low 60 as to be incapable of generating enough fluid pressure to separate the contacts, separation is positively effected by bellows 482.

In the foregoing description there has been specifically disclosed novel circuit breaker constructions especially of the self-contained type, 65 which are adapted to automatically reclose a circuit after a circuit interrupting operation thereof, and in the event of a plurality of closely successive interrupting operations, the breaker is 70 adapted to automatically reclose the circuit a predetermined number of times, after which the breaker contacts are automatically locked in an open circuit position, requiring a manual resetting operation to again place the breaker in service. More specifically, the various embodiments

of circuit breakers disclosed, generally utilize fluid pressure developed by an arc struck when the contacts are slightly separated either by a mechanical means electroresponsively controlled, or directly by electroresponsive means, to obtain overtravel of the contacts to extinguish the arc. Also various lockout schemes have been disclosed which are especially adapted for use with the fluid pressure type of contact separating means, and these include either mechanical counting means, or means for locking the breaker open controlled by a timing means which is set into operation by the first circuit interruption of any series of successive interrupting operations to lock the contacts open after a predetermined time has elapsed. There has also been disclosed lockout means which is controlled directly by electroresponsive means for initiating contact separation. There has also been herein disclosed a breaker of the type employing pressure separation of the contacts which is especially designed to operate on both high and low currents, and this is accomplished either by special design of the arc chamber, or by an auxiliary electroresponsive means for positively producing contact separation on low current interruptions.

Having described preferred embodiments of the invention in accordance with the patent statutes, it is desired that the invention be not limited to the particular embodiments herein disclosed, inasmuch as it will be obvious particularly to persons skilled in the art that many changes and modifications may be made in these particular structures without departing from the broad spirit and scope of this invention. Accordingly, it is desired that the invention be interpreted as broadly as possible, and that it be limited only by what is expressly stated in the following claims and by the prior art.

I claim as my invention:

1. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be effective to move said one contact outwardly with respect to said chamber and cause said further contact separation, fixed partition means having a single aperture in which said one contact is slidably mounted, said partition means forming in said chamber a sub-chamber in which the initial separation of said contacts occurs to effectively utilize the fluid pressure developed by small current arcs, and said slideable contact also being slideable through said aperture to permit the drawing of large current arcs outside of said sub-chamber.

2. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be ef-

fective to move said one contact outwardly with respect to said chamber and cause said further contact separation, fixed partition means having a single aperture in which said one contact is slidably mounted, said partition means forming in said chamber a small sub-chamber in which the initial separation of said contacts occurs to effectively utilize the fluid pressure developed by small current arcs, said slideable contact also being slideable through said aperture to permit the drawing of large current arcs outside of said sub-chamber, and means for moving said contacts into engagement in response to the extinction of said arc.

3. In a circuit interrupter, an arc chamber which is closed at least during circuit interruption, separable contacts adapted to establish an arc in said chamber, means operable in response to a condition of the circuit for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be effective to move said one contact outwardly with respect to said chamber and cause said further contact separation, fixed partition means having a single aperture in which said one contact is slidably mounted, said partition means forming in said chamber a small sub-chamber in which the initial separation of said contacts occurs to effectively utilize the fluid pressure developed by small current arcs, and said slideable contact also being slideable through said partition means to permit the drawing of large current arcs outside of said sub-chamber.

4. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be effective to move said one contact outwardly with respect to said chamber and cause said further contact separation, spaced partitions each having a single aperture in which said one contact is slidably mounted, said partitions dividing said chamber into compartments, whereby when said contacts separate the arc is drawn through said compartments successively.

5. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be effective to move said one contact outwardly with respect to said chamber and cause said further contact separation, and resilient means biasing said contacts into engagement and including a plurality of coil springs arranged coaxially with said one contact

and reacting between said one contact and a relatively fixed abutment.

6. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be effective to move said one contact outwardly with respect to said chamber and cause said further contact separation, resilient means biasing said contacts into engagement and including coaxially arranged coil springs reacting between said one contact and a relatively fixed abutment with said springs adapted to be stressed in tension and compression, respectively, upon movement of said one contact away from the other of said contacts.

7. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber whereby the fluid pressure generated by said arc will be effective to move said one contact outwardly with respect to said chamber and cause said further contact separation, and resilient means in said chamber for biasing said contacts into engagement, and including coaxially arranged coil springs reacting between said one contact and a wall of said chamber.

8. In a circuit interrupter, an arc chamber which is closed at least during circuit interruption, separable contacts in said chamber at least one of which is slidably mounted in an aperture provided in one wall of said chamber, means biasing said slideable contact into engagement with the other of said contacts, actuating means for moving said slideable contact away from the other of said contacts at least an amount sufficient to draw an arc, said slideable contact being movable way from said other contact independently of said actuating means in response to fluid pressure developed by said arc in said chamber, control means for controlling said actuating means to open the circuit and including a plurality of movable, relatively offset control portions, and electroresponsive means normally maintaining said control means in an inactive position and operative in response to predetermined circuit conditions to move in one direction to successively release said control portions and cause successive circuit interrupting operations, and means responsive to the absence of said predetermined circuit conditions for resetting said control means.

9. In a circuit interrupter, separable contacts, means for interrupting the circuit including a plurality of spaced relatively offset control portions movable to cause separation of said contacts to interrupt the circuit, and electroresponsive means engageable with said portions for normally maintaining said circuit interrupting means in an inactive position and operative in response to predetermined circuit conditions to move in the direction said portions are offset to

successively release said control portions and cause successive circuit interrupting operations, means responsive to the absence of said predetermined circuit conditions for resetting said circuit interrupting means, and means responsive to a circuit interrupting operation for reclosing said contacts.

10. In a circuit interrupter, separable contacts, means for interrupting the circuit including a plurality of spaced relatively offset control portions movable to cause separation of said contacts to interrupt the circuit, electroresponsive means engageable with said portions for normally maintaining said circuit interrupting means in an inactive position and operative in response to predetermined circuit conditions to move in the direction in which said portions are offset to successively release said control portions and cause successive circuit interrupting operations, means responsive to the absence of said predetermined circuit conditions for resetting said circuit interrupting means, means responsive to a circuit interrupting operation for reclosing said contacts, and means responsive to a predetermined number of successive interrupting operations to release all of said control portions for preventing reclosure of said contacts.

11. In a circuit interrupter, separable contacts, means for interrupting the circuit including a plurality of levers for causing separation of said contacts, said levers having relatively offset latch portions, electroresponsive means normally engaging said latch portions for maintaining said levers in inactive positions and operative in response to predetermined circuit conditions to move in one direction and successively release said latch portions to thereby cause successive circuit interrupting operations, and said electroresponsive means movable in an opposite direction to normal position in response to the absence of said predetermined circuit conditions to reset said levers in their aforesaid normal position.

12. In a circuit interrupter, separable contacts, means for interrupting the circuit including a plurality of relatively offset control portions movable to cause separation of said contacts to interrupt the circuit, electroresponsive means normally maintaining said circuit interrupting means in an inactive position and operative in response to predetermined circuit conditions to move in one direction to successively release said control portions and cause successive circuit interrupting operations, means responsive to the absence of said predetermined circuit conditions for resetting said circuit interrupting means, means responsive to a circuit interrupting operation for reclosing said contacts, means responsive to release of all of said control portions for preventing reclosure of said contacts, and said resetting means including timing means actuated in response to a first circuit interrupting operation to reset said circuit interrupting means a predetermined time thereafter.

13. In a circuit interrupter, an arc chamber which is closed at least during circuit interruption, a contact member in said chamber, a contact rod slidably mounted through a wall of said chamber into and out of engagement with said contact member and biased into engagement with said contact member, toggle means connected at one end to said rod and having the other end mounted for movement substantially in the direction of movement of said rod, means limiting movement of said other end of said toggle toward said contact member so that in the engaged posi-

tion of said contact rod and contact member said toggle means is maintained adjacent its dead center position, means biasing said toggle means to break the toggle and move said contact rod away from said contact member, latch means normally restraining said biasing means, and electro-responsive means operative to release said latch means and permit said toggle biasing means to open the circuit and establish an arc, and said toggle means permitting overtravel of said contact rod in response to pressure developed in said chamber by the arc.

14. In a circuit interrupter, an arc chamber which is closed at least during circuit interruption, a contact member in said chamber, a contact rod slidably mounted through a wall of said chamber into and out of engagement with said contact member and biased into engagement with said contact member, toggle means connected at one end to said rod and having the other end mounted for movement substantially in the direction of movement of said rod, means limiting movement of said other end of said toggle toward said contact member so that in the engaged position of said contact rod and contact member said toggle means is maintained adjacent its dead center position, means biasing said toggle means to break the toggle and move said contact rod away from said contact member, latch means normally restraining said biasing means, electro-responsive means operative to release said latch means and permit said toggle biasing means to open the circuit and establish an arc, said toggle means permitting overtravel of said contact rod in response to pressure developed in said chamber by the arc, and means operative in response to said overtravel for resetting said toggle means in a position to be reengaged by said latch means upon movement of said contact rod into engagement with said contact member.

15. In a circuit interrupter, an arc chamber which is closed at least during circuit interruption, a contact member in said chamber, a contact rod slidably mounted through a wall of said chamber into and out of engagement with said contact member and biased into engagement with said contact member, toggle means connected at one end to said rod and having the other end mounted for movement substantially in the direction of movement of said rod, means limiting movement of said other end of said toggle toward said contact member so that in the engaged position of said contact rod and contact member said toggle means is maintained adjacent its dead center position, means biasing said toggle means to break the toggle and move said contact rod away from said contact member, latch means normally restraining said biasing means, control means operative to release said latch means and permit said toggle biasing means to open the circuit and establish an arc, said toggle means permitting overtravel of said contact rod in response to pressure developed in said chamber by the arc, means operative in response to said overtravel for resetting said toggle means in a position to be reengaged by said latch means upon movement of said contact rod into engagement with said contact member, said control means including a plurality of movable, relatively offset control portions, electroresponsive means normally maintaining said control means in an inactive position and operative in response to predetermined circuit conditions to move in one direction to successively release said control por-

tions and cause successive circuit interrupting operations, and means responsive to the absence of said predetermined circuit conditions for resetting said control means.

16. In a circuit interrupter, an arc chamber which is closed at least during circuit interruption, separable contacts adapted to establish an arc in said chamber, snap acting electroresponsive means operative in response to predetermined circuit conditions for moving one of said contacts away from the other an amount at least sufficient to establish an arc, the other of said contacts being movable away from said one contact to further increase separation of said contacts independently of said electroresponsive means, said other contact being slidably mounted in an aperture provided in a wall of said chamber, whereby the fluid pressure generated by said arc will be effective to cause said further contact separation.

17. In a circuit interrupter, an arc chamber which is closed at least during circuit interruption, separable contacts adapted to establish an arc in said chamber, electroresponsive means operative in response to predetermined circuit conditions for moving one of said contacts away from the other an amount at least sufficient to establish an arc, the other of said contacts being movable away from said one contact to further increase separation of said contacts independently of said electroresponsive means, said other contact being slidably mounted in an aperture provided in a wall of said chamber, whereby the fluid pressure generated by said arc will be effective to cause said further contact separation.

18. In a circuit interrupter, an arc chamber which is closed at least during circuit interruption, separable contacts adapted to establish an arc in said chamber, electroresponsive means operative in response to predetermined circuit conditions for moving one of said contacts away from the other an amount at least sufficient to establish an arc, the other of said contacts being movable away from said one contact to further increase separation of said contacts independently of said electroresponsive means, said other contact being slidably mounted in an aperture provided in a wall of said chamber, whereby the fluid pressure generated by said arc will be effective to cause said further contact separation, means for moving said other contact toward said one contact in response to a circuit interrupting operation, and said electroresponsive means being operative a predetermined time after a circuit interrupting operation to reset said one contact into engagement with said one contact.

19. In a circuit interrupter, an arc chamber which is closed at least during circuit interruption, separable contacts adapted to establish an arc in said chamber, electroresponsive means controlling a toggle for moving one of said contacts toward and away from the other of said contacts to close the circuit, and open the same at least an amount sufficient to establish an arc, respectively, and the other of said contacts being movable away from said one contact to further increase separation of said contacts independently of said electroresponsive means, said other contact being slidably mounted in an aperture provided in a wall of said chamber, whereby the fluid pressure generated by said arc will be effective to cause said further contact separation.

20. In a circuit interrupter, a closed arc chamber, separable contacts adapted to establish an arc in said chamber, electroresponsive means controlling a toggle for moving one of said contacts toward and away from the other of said contacts to close the circuit, and open the same at least an amount sufficient to establish an arc,

respectively, and the other of said contacts being movable away from said one contact to further increase separation of said contacts independently of said electroresponsive means, said other contact being slidably mounted in an aperture provided in a wall of said chamber, whereby the fluid pressure generated by said arc will be effective to cause said further contact separation, and a second slower acting electroresponsive means for locking said toggle in a position to maintain said contacts out of engagement in response to a plurality of operations of said first mentioned electroresponsive means.

21. In a circuit interrupter, an arc chamber which is closed at least during circuit interruption, separable contacts in said chamber, electroresponsive means for separating said contacts at least an amount sufficient to establish an arc, at least one of said contacts being slidably mounted through a wall of said chamber and being capable of movement away from the other of said contacts independently of said electroresponsive means to increase the separation of said contacts by the force exerted by pressure generated by the arc in said chamber on said one contact, and a time delay electroresponsive means for separating said contacts an amount further than said first mentioned electroresponsive means, whereby to insure sufficient contact separation to extinguish the arc formed, irrespective of the current value thereof.

22. In a circuit interrupter, an arc chamber which is closed at least during circuit interruption, separable contacts in said chamber, electroresponsive means for separating said contacts at least an amount sufficient to establish an arc, at least one of said contacts being slidably mounted through a wall of said chamber and being capable of movement away from the other of said contacts independently of said electroresponsive means to increase the separation of said contacts by the force exerted by pressure generated by the arc in said chamber on said one contact, a time delay electroresponsive means for separating said contacts an amount further than said first mentioned electroresponsive means, whereby to insure sufficient contact separation to extinguish the arc formed, irrespective of the current value thereof, and said time delay electroresponsive means having a lost motion connection with said contacts to permit said further contact separation under the influence of pressures developed by the arc independently of said second electroresponsive means.

23. In a circuit interrupter, an arc chamber which is closed at least during circuit interruption, separable contacts in said chamber, electroresponsive means for separating said contacts at least an amount sufficient to establish an arc, at least one of said contacts being slidably mounted through a wall of said chamber and being capable of movement away from the other of said contacts independently of said electroresponsive means to increase the separation of said contacts by the force exerted by pressure generated by the arc in said chamber on said one contact, and a second electroresponsive means for separating said contacts an amount further than said first mentioned electroresponsive means, whereby to insure sufficient contact separation to extinguish the arc formed irrespective of the current value thereof, said second electroresponsive means being normally independent of the circuit through the interrupter, and means responsive to operation of said first electroresponsive

means to separate said contacts, for connecting said second electroresponsive means in the circuit.

24. In a circuit interrupter, separable contacts, means for interrupting the circuit including a plurality of spaced relatively offset control portions movable to cause separation of said contacts to interrupt the circuit, and electroresponsive means including a bimetal element engageable with said portions for normally maintaining said circuit interrupting means in an inactive position and operative in response to predetermined circuit conditions to move in the direction said portions are offset to successively release said control portions and cause successive circuit interrupting operations, means responsive to the absence of said predetermined circuit condition for resetting said circuit interrupting means, said bimetal being movable in the opposite direction to reengage said portions upon cooling thereof, and means responsive to a circuit interrupting operation for reclosing said contacts.

25. In a circuit interrupter, a contact member, a contact rod slidably mounted for movement into and out of engagement with said contact member and biased into engagement with said contact member, toggle means connected at one end to said rod and having the other end mounted for movement substantially in the direction of movement of said rod, means limiting movement of said other end of said toggle toward said contact member so that in the engaged position of said contact rod and contact member said toggle means is maintained adjacent its dead center position, means biasing said toggle means to break the toggle and move said contact rod away from said contact member, latch means normally restraining said biasing means, and electroresponsive means operative to release said latch means and permit said toggle biasing means to open the circuit and establish an arc.

26. In a circuit interrupter, an arc chamber which is closed at least during circuit interruption, separable contacts adapted to establish an arc in said chamber, a snap-acting bimetal element for moving one of said contacts away from the other an amount at least sufficient to establish an arc, the other of said contacts being movable away from said one contact to further increase separation of said contacts independently of said bimetal element, said other contact being slidably mounted in an aperture provided in a wall of said chamber, whereby the fluid pressure generated by said arc will be effective to cause said further contact separation.

27. In a circuit interrupter, an arc chamber which is closed at least during circuit interruption, separable contacts adapted to establish an arc in said chamber, an opening in said chamber, a flexible bimetal element secured in said opening, one of said contacts mounted on said element so as to be moved thereby away from the other an amount at least sufficient to establish an arc, the other of said contacts being movable away from said one contact to further increase separation of said contacts independently of said element, said other contact being slidably mounted in an aperture provided in a wall of said chamber, whereby the fluid pressure generated by said arc will be effective to cause said further contact separation.

28. In a circuit interrupter, separable contacts, electroresponsive means for separating said contacts to interrupt the circuit, means responsive to a circuit interrupting operation for reclosing said

contacts, timing means adapted to be actuated only by the first interrupting operation of any series of closely successive interrupting operations, and means movable by said timing means a predetermined time after actuation thereof to block reclosing movement of said contacts.

29. In a circuit interrupter, an arc chamber which is closed at least during circuit interruption, separable contacts adapted to establish an arc in said chamber, electroresponsive means connected to the knee of a toggle for moving one of said contacts toward and away from the other of said contacts to close the circuit, and open the same at least an amount sufficient to establish an arc, respectively, and the other of said contacts being movable away from said one contact to further increase separation of said contacts independently of said electroresponsive means, said other contact being slidably mounted in an aperture provided in a wall of said chamber, whereby the fluid pressure generated by said arc will be effective to cause said further contact separation.

30. In a circuit interrupter, an arc chamber which is closed at least during circuit interruption, separable contacts adapted to establish an arc in said chamber, a coiled helically arranged bimetal element connected to the knee of a toggle for moving one of said contacts toward and away from the other of said contacts to close the circuit, and open the same at least an amount sufficient to establish an arc, respectively, and the other of said contacts being movable away from said one contact to further increase separation of said contacts independently of said bimetal element, said other contact being slidably mounted in an aperture provided in a wall of said chamber, whereby the fluid pressure generated by said arc will be effective to cause said further contact separation.

31. In a circuit interrupter, separable contacts, toggle means for moving said contacts into and out of engagement, and a bimetal element connected with the knee of said toggle means to automatically actuate said contacts in response to predetermined conditions.

32. In a circuit interrupter, separable contacts, means for interrupting the circuit including a plurality of control portions independently movable to cause separation of said contacts to interrupt the circuit, electroresponsive means engageable with said portions for normally maintaining said circuit interrupting means in an inactive position and operative in response to predetermined circuit conditions to move in one direction, means responsive to movement of said electroresponsive means in said one direction to successively release said control portions and cause successive circuit-interrupting operations, means responsive to the absence of said predetermined circuit condition for resetting said circuit-interrupting means, and means responsive to a circuit-interrupting operation for reclosing said contacts.

33. In a circuit interrupter, an arc chamber which is closed at least during circuit interruption, a contact member in said chamber, a contact rod slidably mounted through a wall of said chamber into and out of engagement with said contact member and biased into engagement with said contact member, toggle means connected at one end to said rod and having the other end mounted for movement substantially in the direction of movement of said rod, means limiting movement of said other end of said

toggle toward said contact member so that in the engaged position of said contact rod and contact member said toggle means is maintained adjacent its dead center position, means biasing said toggle means to break the toggle and move said contact rod away from said contact member, latch means normally restraining said biasing means, electroresponsive means operative to release said latch means and permit 5 said toggle biasing means to open the circuit and establish an arc, said toggle means permitting overtravel of said contact rod in response to pressure developed in said chamber by the arc, and time delay means associated with said 10 other end of said toggle for delaying circuit closing movement of said contact rod.

34. In a circuit interrupter, an arc chamber which is closed at least during circuit interruption, separable contacts adapted to establish an 20 arc in said chamber, time delay electroresponsive means operative a predetermined time after the occurrence of predetermined circuit conditions for moving one of said contacts away from the other an amount at least sufficient to establish an arc, the other of said contacts being movable away from said one contact to further increase separation of said contacts independently of said electroresponsive means, said other contact being slidably mounted in an aperture provided in a wall of said chamber, whereby 30 the fluid pressure generated by said arc will be effective to cause said further contact separation, means for moving said other contact toward said one contact in response to a circuit interrupting operation, and said electroresponsive means being operative a predetermined time after a circuit interrupting operation to reset said one contact into engagement with said one contact.

40. 35. In a circuit interrupter, separable contacts, electroresponsive means for separating said contacts to interrupt the circuit, means responsive to a circuit interrupting operation for reclosing said contacts, timing means adapted 45 to be actuated to an active position only by the first interrupting operation of any series of closely successive interrupting operations, said timing means slowly returning from said active position to a position where it is again adapted 50 to be actuated upon a circuit interrupting operation, and said timing means having an intermediate position at which it is operative to prevent a reclosure of said contacts.

36. In a circuit interrupter, separable contacts, 55 toggle means for moving said contacts into and out of engagement, and a coiled, helically arranged bimetal element connected with the knee of said toggle means to automatically actuate said contacts in response to predetermined conditions.

60. 37. In a circuit interrupter, an arc chamber which is closed at least during circuit interruption, separable contacts adapted to establish an arc in said chamber, means for separating said contacts to establish an arc, at least one of said contacts being capable of movement away from the other of said contacts to further increase separation of said contacts independently of said contact separating means, said one contact slidably mounted in an aperture provided in a wall of said chamber 65 whereby the fluid pressure generated by said arc will be effective to move said one contact outwardly with respect to said chamber and cause said further contact separation, and resilient means in said chamber for biasing said contacts 70 into engagement.

38. In an automatic reclosing circuit breaker, separable contacts, electroresponsive means for separating said contacts in response to predetermined electrical conditions, and means biasing said contacts closed to automatically close said contacts in response to a circuit interrupting operation comprising a pair of coaxially arranged springs arranged to be stressed in tension and compression, respectively, in response to separation of said contacts.

39. In an automatic reclosing circuit breaker, separable contacts, an actuating rod slidably mounted for movement in opposite directions for actuating said contacts into and out of engagement, electroresponsive means for moving said actuating rod in a direction to separate said contacts in response to predetermined electrical conditions, and means biasing said contacts closed to automatically close said contacts in response to a circuit interrupting operation comprising a pair of coaxially arranged springs telescoped over said rod and arranged to be stressed in tension and compression, respectively, in response to separation of said contacts.

40. In a circuit interrupter, a closed arc chamber, separable contacts adapted to establish an arc in said chamber, electroresponsive means controlling a toggle for moving one of said contacts toward and away from the other of said contacts to close and open the circuit, respec-

tively, and a second slower acting electroresponsive means for locking said toggle in a position to maintain said contacts out of engagement in response to a plurality of operations of said first mentioned electroresponsive means.

5 41. In a circuit interrupter, a closed arc chamber, separable contacts adapted to establish an arc in said chamber, electroresponsive means for moving one of said contacts toward and away from the other of said contacts to close and open the circuit, respectively, and a second slower acting electroresponsive means for positively locking said one contact in a position to maintain said contacts out of engagement in response to a plurality of operations of said first mentioned electroresponsive means.

10 42. In an automatic reclosing circuit breaker, separable contacts, toggle means for moving said contacts into and out of engagement, electroresponsive means normally holding said toggle against collapse in the closed circuit position of said contacts and operable in response to predetermined electrical conditions to release said toggle to permit said contacts to separate, and 15 second current responsive means operable in response to a circuit interrupting operation for resetting said toggle means to automatically reclose said contacts.

JOHN K. HODNETTE.
